ANTIAIRCRAFT SHELL

Charles Unterberg, Mobile, Ala.

Application March 8, 1943, Serial No. 478,374

2 Claims. (Cl. 102—63)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to improvements in shells or projectiles and has for one of its primary objects the provision of a novel and improved shell which is especially adapted for anti-aircraft use.

More specifically it is an object of the invention to provide a shell which will be effective for disabling aircraft or obstructing the maneuvers thereof without requiring the shell to directly hit the aircraft and is effective even though the shell explodes at a point remote from the aircraft.

It is a further object of the invention to provide an anti-aircraft shell having a retarded descent obstruction or aircraft disabling expedient which is rendered effective for the purpose specified upon the bursting of the shell.

These and other objects of the invention will become apparent from a reading of the following specification in connection with the accompanying drawing which illustrates a preferred embodiment having the characteristics of my invention and by which the same may be practiced.

Fig. 1 is an elevational view of the anti-aircraft shell partially sectionalized to illustrate the interior construction and assembly, while Fig. 2 is illustrative of the retarded descent obstruction released upon the bursting of the shell.

The shell shown in the drawing to illustrate an embodiment of the invention includes a shell casing 5 having an annular recess 6 extending from the forward end 7 of the casing 5 into walls thereof intermediately of their surfaces and substantially concentric therewith. The base portion 8 of the recess 6 is utilized as a powder magazine for a charge 9. The shell nose piece 10 is provided at its base 11 with an extending annular flange or lip 12 adapted to extend into the recess 6 and cooperates with the inner surfaces thereof for the journaling of the nose piece to the shell casing. The annular lip flange 12 also serves to enclose the charge 9 within the recess 6. Upon the forward end of the nose piece 10 is provided a time fuse 13 from which a powder train or a fuse 14 extends to and through the annular flange 12 into firing communication with the charge 9.

Within the shell casing 5 there is provided a great length of cable 15 in coiled formation. One end of the cable 15 is secured to the base of the shell casing 5 by any suitable means, such

as by tying the cable end to a loop 16 on the inner base surface of the shell casing. To the other end of the cable 15 there is attached a suitable parachute 17 folded into the shell casing 5 in a compact manner to prevent fouling. The forward end of the folded parachute 17, which is the crown of the 'chute when in extended position, is secured by suitable means, such as a tie 18, to the inner forward portion of the nose piece 10.

In operation, the time fuse 14 is set to allow predetermined flight or altitude igniting the charge 9. When the charge is ignited, the nose piece 10 is caused to be separated from the shell casing 5 and, by reason of the parachute tie 18, the parachute 17 is caused to be withdrawn from the casing 5. The tie 18 is of such strength as may be readily broken by the momentum of the nose, from the casing, when the 'chute is drawn taut. Once the 'chute is freed of the nose piece, the weight of the shell casing 5 together with the coil of cable 15, as it speeds earthward, causes the parachute 17 to be extended. The retarded parachute 17 on the forward end of the cable 15, and the weight of the shell casing 5 on the other end of the cable 15 subjects the cable to tension, thereby causing it to uncoil and hang streamer-like from the 'chute, as shown in Fig. 2, as an obstruction intended to foul the control of aircraft.

A barrage of such obstruction would be extremely effective, particularly because the cables would be difficult to see even in clear skies and even though sighted would be difficult to avoid because of their constantly changing positions.

Having described my invention and illustrated an embodiment by which the same may be practiced, what I claim is:

1. An anti-aircraft shell comprising a casing open at one end and having a recess extending from said open end into the walls of the casing, a shell separating explosive charge within said recess, a shell nose piece having a portion extending from the base thereof into said recess, said extending portion serving as means for inclosing said charge within said recess and as means cooperating with the walls of said recess for journaling said nose piece and casing, a time fuse carried by said nose piece, a fuse extending from said time fuse into igniting relationship with said explosive, a parachute within said shell, tie means of predetermined tensile strength securing the canopy of said parachute to said nose piece, and a coil of cable within said shell having one end secured to said shell casing and its other

end secured to the shroud lines of said parachute.

2. An anti-aircraft shell comprising a casing open at one end and having a recess extending from said open end into the walls of the casing, a shell nose piece having a portion extending from the base thereof into said recess as means cooperating with the walls of said recess for journaling said nose piece and casing, a time fuse carried by said nose piece, an explosive charge

inclosed within said recess by said nose extending portion, means whereby said charge may be ignited by said time fuse, a parachute within said shell, tie means of predetermined tensil strength securing the canopy of said parachute to said nose piece, and a coil of cable within said shell having one end secured to said shell casing and its other end secured to the shroud lines of said parachute.
